Attorney.

UNITED STATES PATENT OFFICE

JOSEPH ALFRED MILLS, OF EAST KIRKBY, ENGLAND

KNITTING MACHINE

Application filed February 14, 1929, Serial No. 339,837, and in Great Britain February 24, 1928.

This invention relates to improvements in knitting machines of the kind in which butted needles are located in gates or recesses (usually termed tricks) in a needle cylinder or bed, and motion is imparted to them by means of cams acting on the needle butts. Its object is to provide more strength in the walls between the needle tricks at the points where the butts on the needles are located, than is 10 the case in existing machines.

The invention is applicable to machines of very fine gauge, where there is very little space between the needles, and the walls between the needle tricks are consequently very 15 thin and not strong enough to resist the lateral pressure which is put upon them by the action of the cams on the needle butts. Where this weakness occurs in a machine, it has to be run at a reduced speed, and the output is in 20 consequence seriously limited.

A machine which comes under this head, is the circular rib machine adapted to produce a one-and-one interlocked ribbed fabric. In this machine, alternate needles in the cylinder 25 and alternate needles in the ribber dial knit one course, whilst the remainder knit the next course. There are therefore two sets of both cylinder and rib needles, and there is in consequence very little space between them.

30 It is obvious that the strength in the walls between the needle tricks, is more particularly required where the needle butts are disposed, and lateral pressure is put upon them by the cams acting upon the said butts. The arrangement hereinafter described provides the necessary strength at the said parts.

The invention is described and shown as applied to a circular knitting machine, that being the type where it is more particularly 40 required, but it is also applicable to machines in which the needles are disposed in a straight bed.

According to this invention, short and long needles are arranged alternately in a needle cylinder, straight bed, or ribber dial, the

butted ends of the long needles are disposed in tricks formed in a part which stands up above the tricks in which the corresponding ends of the short needles are disposed, said upstanding part being an exterior enlargement in the case of a needle cylinder, and a raised step in the case of a straight bed or ribber dial, and one set of needles is bent in order to locate their upper or outer ends in line with those of the other set. 50

55 Referring to the accompanying drawing:

Fig. 1 is a sectional elevation, showing the needle cylinder and ribber dial of a circular rib knitting machine, both of which are constructed and the needle arranged therein 60 according to my invention.

Fig. 2 is an elevation of a section of the needle cylinder.

Fig. 3 is a sectional plan of a portion of the needle cylinder taken on the line $\alpha\alpha$ of 65 Fig. 1.

Fig. 4 is a plan of a section of the ribber dial.

Fig. 5 is a sectional elevation, and

Fig. 6 a plan of a segment of a ribber dial 70 embodying the same principle as that shown in Fig. 1, but of slightly different construction.

Like letters indicate like parts throughout the drawing. 75

In carrying out this invention, the upper end of the needle cylinder A including the verge B (see Figs. 1, 2 and 3) is formed with needle tricks or recesses C, for the upper ends of the whole of the needles, and the whole of these tricks are carried down to the point D. From the latter point down to the point E, the exterior diameter of the needle cylinder is increased, and every alternate trick C is carried down to the lower end of this enlargement, that is, to E. 80

At a still lower point, that is from E to F, the external diameter of the needle cylinder is still further increased, and this part is formed with needle tricks G, which register 85

with the spaces between the needle tricks C which are carried down the part between D and E. In the preferred construction, but it is not essential, the part of the cylinder A between D and E, is of such a diameter that the tricks G can be continued through it, but they are of a reduced depth at this part.

The short needles H, are disposed in alternate tricks C in the upper part of the cylinder A, and have their lower butted ends H¹ located in the tricks C of full depth between the points D and E, whilst the long needles J have their lower butted ends J¹ located in the tricks G between the points E and F. These long needles J which are also located in the shallow tricks G in the part between D and E, are bent at K, so as to locate their upper ends in the same line as the short needles H, and in the tricks C in the upper part of the needle cylinder A.

It will be seen that with the arrangements described, the walls between the tricks where the butted ends of both the long and short needles are disposed, are more than double the strength of the walls between the tricks where the upper ends of the said needles are disposed, and as ample strength is afforded where it is required, the space between the needles can be reduced to the minimum, and consequently the number employed per inch can be increased to the maximum without the disadvantage previously referred to. Very fine gauge machines with this arrangement can be run at the normal speed without risk of causing damage, and their output is thus brought up to that of medium or coarse gauge machines.

The shallow needle tricks G in the part between the points D and E, in which the long bent needles J are disposed, do not affect the strength of the walls between the tricks in which the butted ends of the short needles H are disposed, as the depth of these tricks is only about one fourth of those C provided at this part of the said ends of the short needles H.

In order to actuate the needles arranged as described, two sets of cams, upper and lower are required, as is usual when needles of different lengths are employed, but in this case, it is obvious that the lower set of cams must be disposed in a cylindrical surface which is greater in diameter than that of the upper set of cams. This can however be obviated if desired by forming the short needles H with longer butts than the long needles J.

The same construction and arrangement is adopted in the rubber dial L of a rib knitting machine, (see Figs. 1 and 4), but in this case, the inner butted ends M¹ of the long rib needles M, are disposed in radial needle tricks Y formed in an inner annular part between N and N¹ which stands up a step higher than the annular part between N¹ and O, in which deep tricks Y¹ are provided for the

butt ends P¹ of the shorter needles P, and shallow tricks Y² for the long needles M. The outer part O to O¹ which is a step lower than the part between N¹ and O, is formed with tricks Y³ for every needle, and the long needles M are bent at M² in order to locate their outer ends in these tricks and in the same plane as the outer ends of the short needles P.

The dial construction shown in Figs. 5 and 6 embodies the same principle as that previously described, but is specially adapted for use in a circular rib knitting machine in which sinkers are employed.

This dial is built up of several members fitted together, and comprises a main part V with an annular recess V¹ in its upper face, in which is fitted an annulus Q of the sectional shape shown. The outer portion V² of the face of the main part V is formed with deep radial gates R for the alternate short rib needles P, and with shallow gates T between the former, for the outer portions of the long dial needles M, the butted ends M¹ of which are disposed in gates S in the part Q¹ of the annulus Q, which part stands a step higher than the part V² of the main part V. The long needles M are in this arrangement bent at U, a point which is outside the circumference of the body of the dial V, the diameter of which must be regulated to make room for the sinkers to work in.

The short needles P are formed with tails P², which work under the annulus Q, whilst the long needles M are also provided with tails M³ which work under a central plate W. This prevents the inner ends of the needles from rising, and obviates the necessity for employing a cam disc which is adapted to hold them down.

What I claim as my invention and desire to secure by Letters Patent is:

In a knitting machine, a vertical needle cylinder having two external circumferential enlargements which form three steps, the intermediate step projecting beyond the upper step, which forms the top part of the cylinder, and the lower step projecting beyond the intermediate step, said upper step having grooves for all the needles and each alternate groove in it being extended through the intermediate step, and said intermediate step having grooves arranged in line with the remaining grooves of the upper step and extended through the lower step and having their bottoms arranged in a different longitudinal plane from those of the grooves in the upper step, said intermediate step being thereby provided with deep and shallow grooves arranged alternately; in combination with short needles arranged in the deep grooves of the intermediate step and the grooves in the upper step in line with the said deep grooves; and long needles arranged in the shallow grooves of the intermediate step and

their extensions through the lower step and having inwardly bent upper end portions which engage with the said remaining grooves of the upper step, all the needles being otherwise straight and having the inner sides of their butts arranged in the same planes as their inner sides which bear on the bottoms of the grooves, and all the needles being withdrawable upwardly in their grooves without displacing them radially of the cylinder.

In testimony whereof I have signed my name to this specification at Nottingham, this 30th day of January, 1929.

JOSEPH ALFRED MILLS.
